UNITED STATES PATENT OFFICE

142,440

DESIGN FOR A GAME BOARD OR SIMILAR ARTICLE

Julius Clarkson Pratt, Eureka, Calif.

Application May 24, 1945, Serial No. 119,701

Term of patent 7 years

(Cl. D34—5)

To all whom it may concern:

Be it known that I, Julius Clarkson Pratt, a citizen of the United States, residing at Eureka, in the county of Humboldt and State of California, have invented a new, original, and ornamental Design for a Game Board or Similar Article, of which the following is a specification, reference being had to the accompanying drawing, forming part thereof.

Figure 1 is a top plan view of a game board or similar article, showing my new design, and Figure 2 is an edge elevational view thereof.

I claim:

The ornamental design for a game board or similar article, as shown.

JULIUS CLARKSON PRATT.
